UNITED STATES PATENT OFFICE.

DOMINICK M. BERNOTOW, OF CHICAGO, ILLINOIS, ASSIGNOR TO BUNTE BROTHERS, OF CHICAGO, ILLINOIS, A CORPORATION OF ILLINOIS.

DEVICE FOR REGULATING HUMIDITY OF CONTAINERS.

Application filed July 21, 1923. Serial No. 652,936.

To all whom it may concern:

Be it known that I, DOMINICK M. BERNOTOW, a citizen of the United States, residing at Chicago, in the county of Cook and State 5 of Illinois, have invented a certain new and useful Improvement in Devices for Regulating Humidity of Containers, of which the following is a specification.

My invention relates to devices for regulating the humidity of containers for candy, tobacco and other goods which are apt either to absorb moisture from the atmosphere or to become too dry if exposed to the atmosphere. The device is especially adapted to 15 be used in connection with jars having covers or stoppers (usually of glass) which are internally chambered. Devices of this type are not basically new, but the object of my invention is to provide a simple and 20 efficient retainer which may be readily applied to or removed from the cover of the jar, and which, when applied, will securely hold its position, present a neat appearance, and prevent its contents from gaining access 25 to the contents of the jar. My device is especially adapted to be used in connection with jar covers which have contracting lower mouths, and one of the specific objects of the invention is to provide a two part 30 retainer, one of which is an expansion member and the other operates to expand it. Contributory objects will become apparent 35 as the description proceeds.

I obtain my objects by the mechanism 40 illustrated in the accompanying drawings in which

Figure 1 is an assembly view showing my retainer in position in the cover of a jar.

Figure 2 is a view showing the retainer 45 detached from the jar cover and showing the retainer with its two chief parts partially, but not entirely separated.

Figure 3 is a perspective view showing 50 the two parts of the retainer separated.

Like numerals refer to like parts throughout the several views.

In the form illustrated, the jar or general container 1 has an internally chambered cover 2, the lower flange 3 whereof converges slightly at its mouth. The outer convergence or taper enables the cover to fit snugly into the neck of the jar, while the interior convergence or taper makes it possible to securely fasten my retainer in the 55 cover. It will be understood that the jar

and cover are known articles of commerce.

Referring now, more particularly, to the parts which embody my invention: The purpose of my device is to mount, in a jar of this character an element 6 which will either absorb moisture from the atmosphere 60 or impart moisture to it according to the requirements of the contents of the jar. For use in a candy jar the element 6 should be an absorbent, because candy, especially when 65 the atmosphere is warm or humid, tends to absorb moisture and become sticky. For convenience, therefore, I will refer to the element 6 as an "absorbent pad." It is illustrated as being of disc form apertured 70 at the center for accommodating the clamping screw 8, hereinafter again referred to.

The two principal members of the retainer are the expansion member 10 and the expander 12. These in conjunction form a 75 retainer or holder for the pad. These members are preferably of metal and of approximately the same diameter as the inner surface of the lower flange 3 of the stopper. These two parts practically form the upper 80 and lower halves of a disc-like box. The lower half is apertured at the bottom so that moisture may pass to the absorbent pad.

The upper half 10 of the retainer has 85 vertical slots 14 in the sides so that the sides may expand and contract. The sides of the lower half 12 converge so as to wedgingly fit into the upper half and expand the sides thereof. It is desirable to form an annular shoulder 16 near the lower edge of the upper 90 half of the retainer for engaging the inner surface of the flange of the stopper or cover of the jar as illustrated in Fig. 1.

A nut 18 is rigidly secured in the top of the upper half 10 and receives the upper 95 end of the clamping screw 8. Near the lower end the set screw has two shoulders 20 which receive between them the bottom of the lower half 12 of the retainer. The result of this construction is that when the screw is rotated the lower half 12 will be 100 raised or lowered relatively to the upper half. By preference the lower end of the screw is provided with a knurled head 22 by which the screw may be easily rotated.

Operation: When it is desired to equip a candy jar with my device an absorbent pad 6 is placed in the lower half or "expander" 105 of my retainer, and the screw 8 then is screwed part way into the nut 18 whereupon 110

the parts will have the relative position suggested in Figure 2. Next the retainer is raised into the flange 3 of the cover and the screw is then rotated further. This draws 5 the lower half 12 of the retainer upward, forcing its converging sides into engagement with the lower rim of the upper half of the retainer causing the sides to expand and engage the inner surface of the flange 3 10 of the cover. By screwing the screw sufficiently tight the expansion member 10 will so tightly engage the cover as to securely hold the retainer in place as shown in Fig. 1. The lower half or expander 12 acts as a 15 wedge, and this taken in connection with the powerful drawing effect of the screw makes it possible to obtain a high degree of outward pressure against the flange of the cover. Consequently the retainer may 20 be held very securely even though the taper of the inner surface of the cover rim is rather slight.

My device also has another advantage and that is that its range of expansion is sufficient to enable it to fit into jar covers of 25 considerably different size of flange. These jar covers are made in large quantities and there is frequently considerable variation in diameter between the various individual 30 covers, but my retainer has a considerable range of adjustment and may be made to retain itself in covers which differ considerably in size.

Having thus described my invention what 35 I claim as new and desire to secure by Letters Patent is:

1. A device for regulating the humidity of containers comprising a retainer for holding the moisture regulating substance, said 40 retainer consisting of an expansion member

and an expander adapted to wedgingly engage the same for expanding the walls thereof.

2. A device for regulating the humidity of containers comprising a two-part receptacle for the moisture regulating substance, one part having an annular, expandible wall and the second part having an annular tapered flange for expanding said wall when forced into it, and means for 45 forcing said second part into the first part 50 for causing it to expand and engage the wall of the container.

3. A device for regulating the humidity of containers, said device having an annular 55 receptacle formed of two principal parts, the upper part having a circular top and a depending flange and the lower part having a circular, apertured, bottom and an upstanding flange; and means for drawing said parts 60 toward each other, the flange of one of the parts being slotted to render it expandible and the flange of the other part being tapered to enable it to expand the slotted flange when drawn into it and cause it to 65 engage the wall of the container.

4. A device for regulating the humidity of containers, said device having a receptacle formed of two principal parts, the upper part having a circular top and a slotted depending flange, and the lower part having a circular, apertured, bottom and an upstanding converging flange, and a screw for forcing the converging flange into the slotted flange for causing it to expand and engage 70 75 the wall of the container.

In witness whereof, I have hereunto subscribed my name.

DOMINICK M. BERNOTOW.
